ATTORNEY

UNITED STATES PATENT OFFICE.

SAMUEL SWAIN, OF GRAPEVILLE, PENNSYLVANIA.

RAIL-JOINT.

1,105,220.

Specification of Letters Patent. Patented July 28, 1914.

Application filed April 18, 1914. Serial No. 832,885.

To all whom it may concern:

Be it known that I, SAMUEL SWAIN, a citizen of the United States of America, residing at Grapeville, in the county of Westmoreland and State of Pennsylvania, have invented certain new and useful Improvements in Rail-Joints, of which the following is a specification, reference being had therein to the accompanying drawing.

10 This invention relates to a rail joint and has for its object to provide a device of such class, in a manner as hereinafter set forth, for connecting the opposing ends of a pair of track rails together without the employment of nuts and bolts, at the same time providing for the necessary contraction and expansion of the track rails due to climatic influences.

Further objects of the invention are to 20 provide a rail joint which is simple in its construction and arrangement, strong, durable, efficient and convenient in its use, readily set up and comparatively inexpensive to manufacture.

25 With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

30 In describing the invention in detail, reference is had to the accompanying drawings in which:—

Figure 1 is a side elevation of a rail joint in accordance with this invention; Fig. 2 is a sectional plan; Fig. 3 is a transverse sectional view; Fig. 4 is a side elevation, broken away, of the track rails; Fig. 5 is a perspective view of one of the splice bars.

Referring to the drawings in detail, 6 and 45 7 denote a pair of track rails and each of which includes a head 8, web 9, and a base 10. The opposing ends of the web 9 of the track rails 6—7 are each provided with a longitudinally extending T-shaped slot 11, and the stem of one slot is arranged in alignment with the stem of the other slot, thereby providing, when the track rails 6—7 are in position, what may be termed an H-shaped opening.

50 Arranged at one side of the webs 9 of the track rails 6—7, is a splice bar 12 which en-

gages the heads 8 and bases 10 of the rails, and is spaced from the webs 9. The splice bar 12 is provided with an H-shaped opening 13 which is arranged in alignment with the H-shaped opening formed by the T-shaped slots 11 in the webs 9. Arranged above the opening 13, and on the outer face of the splice bar 12, is a pin 14, having pivotally mounted thereon a cam 15, and the outer face of the splice bar 12 is further provided with a pin 16 having pivotally mounted thereon one end of a locking dog 17, which is capable of being engaged by the cam 15, whereby said dog is maintained in locking position for a purpose to be herein-after referred to.

The reference character 18 denotes a splice bar which is arranged upon the sides of the track rails 6—7, opposite the sides which are opposed by the splice bar 12, and the said splice bar 18 engages the heads 8 and bases 10 of the track rails 6—7. The inner face of the splice bar 18 has formed integral therewith an H-shaped coupling arm 19, 80 formed with notches 20 which provide seats for a locking member to be presently referred to. The arm 19 extends through the H-shaped opening, formed by the T-shaped slots 11, and furthermore extends through 85 the H-shaped opening 13 in the splice bar 12, as well as projecting outwardly from the said splice bar 12.

Mounted in the seats formed by the notches 20 in a locking member 21 formed 90 of a bar of suitable material and which is provided in its top edge with teeth 22, these latter capable of being engaged by the dog 17, and when the latter is maintained in locking position by the cam 15, the splice 95 bars 12—18 are connected together, and under such conditions the track rails 6—7 are coupled in view of the fact that when the locking member 21 is in position, the coupling arm 19 is maintained from transverse 100 movement with respect to the webs 9 of the track rails. The notches 20 have their outer walls inclined and the locking member 21 is wedge-shaped, under such conditions, when the locking member is driven home, it 105 is tightly secured in position. Longitudinal movement of the locking member 21 is arrested through the medium of the dog 17 and cam 15.

What I claim is;—

1. A rail joint comprising the combination with a pair of track rails having the

- webs thereof formed with **T**-shaped slots registering to provide an **H**-shaped opening, of a pair of splice bars arranged at the sides of said rails, one of said splice bars provided 5 with an **H**-shaped opening, an **H**-shaped coupling arm integral with the other of said splice bars and extending through that splice bar provided with an **H**-shaped opening, a wedge-shaped locking member engaging in said coupling arm exteriorly of that splice bar provided with an **H**-shaped opening, and means carried by that splice bar provided with an **H**-shaped opening and engaging in said locking member to prevent 10 longitudinal movement of the locking member.
2. A rail joint comprising the combination with a pair of track rails having the webs thereof formed with **T**-shaped slots 15 registering to provide an **H**-shaped opening, of a pair of splice bars arranged at the sides of said rails, one of said splice bars provided

with an **H**-shaped opening, and **H**-shaped coupling arm integral with the other of said splice bars and extending through that splice bar provided with an **H**-shaped opening, a wedge-shaped locking member engaging in said coupling arm exteriorly of that splice bar provided with an **H**-shaped opening, means carried by that splice bar provided with an **H**-shaped opening and engaging in said locking member to prevent longitudinal movement of the locking member, and a cam carried by said splice bar provided with an **H**-shaped opening and engaging said means for maintaining it in engagement with said locking member.

In testimony whereof I affix my signature in the presence of two witnesses.

SAMUEL SWAIN.
